UNITED STATES PATENT OFFICE.

EDWARD D. MOSBACHER, OF MEADVILLE, PENNSYLVANIA, ASSIGNOR OF ONE-HALF
TO WALTER H. MOSBACHER, OF MEADVILLE, PENNSYLVANIA.

ADJUSTABLE WINDOW SCREEN.

Application filed February 10, 1926. Serial No. 87,426.

This invention relates to improvements in window screens of the laterally adjustable type, an object being to provide a screen which may be retained within the lower portion of the guide groove for the upper window sash and conveniently moved into and out of position beneath the raised lower sash and yet maintain a tight joint when in use.

10 Ordinarily, in the use of adjustable window screens, the screens are positioned within the guide groove for the lower window sash when used at the bottom of the window and when it is desired to close the window, the screen must either be removed entirely, or placed within the guide groove below the upper window sash. When it is again desired to use the screen, it must be either replaced in the guide groove for the 15 lower sash, or, considerable space will be left between the upper portion of the screen and the bottom rail of the lower sash. Flies and other insects may then freely pass.

This and other disadvantages are overcome in the present invention by providing a screen which may at all times remain within the lower portion of the guide groove for the upper sash and conveniently moved into and out of position beneath the lower sash 20 without removing the screen from the groove and yet maintain such contact between the screen and sash as to prevent the passage of insects.

With the above and other objects in view, the invention further includes the following novel features and details of construction, to be hereinafter more fully described, illustrated in the accompanying drawings and pointed out in the appended claims.

40 In the drawings:—

Figure 1 is a vertical sectional view showing a portion of a window with the screen positioned therein but not in use.

Figure 2 is a similar view showing the position of the screen in use.

Figure 3 is a perspective view of the screen partly broken away.

Figure 4 is a fragmentary elevation of the upper part of the screen.

50 Figure 5 is an enlarged section on the line 5—5 of Figure 4.

Referring to the drawings in detail wherein like characters of reference denote corresponding parts, the reference character 10 indicates a portion of a window frame in

which is slidably mounted a lower sash 11 and an upper sash 12, the former being slideable within the usual guide groove 13, while the upper sash is slideable within the usual guide groove 14.

60 The screen comprises a pair of screen sections indicated at 15 and 16. These sections may be of any suitable construction, the section 15 including an upper rail 17 and a lower rail 18, while the section 16 includes 65 an upper rail 19 and a lower rail 20. The rails 17 and 19, and 18 and 20 respectively are slidably connected by any suitable means such as the tongue and groove connections indicated generally at 21 in Figure 70 5 of the drawings. As thus far described, the screen is of the usual laterally adjustable type which is removably positioned within the guide grooves for the sash.

75 The screen structure of the present invention includes a longitudinally adjustable sash engaging ledge which is offset with respect to the screen and which is designed to be engaged by the bottom rail of the lower sash as shown in Figure 2 of the drawings. For 80 this purpose, the upper rail 19 of the screen section 16 has secured thereto a longitudinally disposed strip 22. The upper rail 17 of the section 15 has secured thereto a transversely channel-shaped member 23 which 85 slidably receives the strip 22. The outer end of the strip 22 terminates just short of the end of the screen section 16, while the outer end of the channel-shaped member 23 terminates just short of the adjacent end of 90 the screen section 15. By this means, the screen may be placed within the groove 14 of the upper sash and the longitudinally adjustable ledge defined by the strip 22 and the channel-shaped member 23, and indicated 95 generally at 24 in Figures 1 and 2 of the drawings, will extend inward beneath the lower rail of the lower sash with the ends of the ledge 24 abutting the strip S which separates the grooves 13 and 14. A continuous ledge is thus provided across the window 100 so that there is no opening or recess for the passage of insects.

Normally, the screen is positioned as illustrated in Figure 1 of the drawings and may be brought into use when the window is raised by pulling the upper portion of the screen inward as shown in Figure 2. A finger piece 25 is provided for convenience in positioning the screen.

It is preferred to provide the lower portion of the screen with spacing elements or blocks 26, one of which is positioned adjacent the outer lower edge of each screen section so as to engage the outer walls of the guide grooves 14 and hold the lower portion of the screen inward close to the strip S.

If desired, the member 23 may be provided with spaced openings 27 for the passage 10 of a pin or other suitable fastening device to hold the screen sections in proper separated relation.

The invention is susceptible of various changes in its form, proportions and minor 15 details of construction and the right is herein reserved to make such changes as properly fall within the scope of the appended claim.

Having described the invention what is claimed is:—

20 In a window screen device adapted to be mounted within the grooves of the upper

sash of a window and to remain permanently therein, said screen device comprising laterally-slidably-adjustably connected 25 screen sections including horizontal and vertical bars, the former being slidably connected and the latter being engageable within said grooves for the upper sash, a spacing block mounted at the lower edge of the screen and engageable with the outer wall 30 of the groove for the upper sash, and a horizontal ledge at the inner face of the upper portion of the screen adapted to project into the path of movement of the lower rail of the lower sash for engagement thereby whereby 35 the screen device will be maintained in closing or obstructing relation to the space between the lower ledge of the lower sash, when the sash is raised, and the sill of the window frame.

40 In testimony whereof I affix my signature.

EDWARD D. MOSBACHER.
